UNITED STATES PATENT OFFICE.

BENJIMAN MORTON BIRD, GEORGE C. BIRD, AND DAVID P. BIRD, OF MAITLAND, MISSOURI, ASSIGNORS OF ONE-HALF TO J. B. BRIDGMAN, OF MAITLAND, MISSOURI.

BURIAL VAULT.

Application filed July 11, 1922. Serial No. 574,195.

To all whom it may concern:

Be it known that BENJIMAN M. BIRD, GEORGE C. BIRD, and DAVID P. BIRD, citizens of the United States of America, residing 5 at Maitland, in the county of Holt and State of Missouri, have invented new and useful Improvements in Burial Vaults, of which the following is a specification.

The object of the invention is to provide a 10 comparatively inexpensive and yet strong, light and durable as well as water-tight burial vault; and with this object in view the invention consists in a construction and combination of parts of which a preferred 15 embodiment is shown in the accompanying drawings, wherein:—

Figure 1 is a view in perspective of a complete burial vault with handle attached.

Figure 2 is a transverse sectional view 20 of the same.

Figure 3 is a perspective view of the vault frame showing a portion of the inner lining in place.

Figure 4 is a view of the same showing 25 the outer lining and a portion of the metal lathing in place.

Figure 5 is a detail view of the door detached.

The structure embodies a skeleton frame 30 having longitudinal base and spring bars 10 and 11 and a series of transverse space-frame elements consisting of bottom cross bars 12, uprights 13 and arched bars 14 together with suitable horizontal braces 15 35 and side braces 16. To the inner surfaces of these frame elements is secured an inner lining 17 of wall board and to the exterior surfaces thereof is attached an outer lining 18 also preferably of wall board over which 40 is disposed metal lathing 19 for holding an exterior protective coating of cement or plaster 20 preferably stucco with pebble dash.

One end of the structure is preferably 45 closed by a wall 21 while the other end is fitted with a removable door 22 fitted at its edges in a rabbet 23 formed by applying strips 23' to the inner surfaces of the bottom and side walls. The door is provided with a latch bar 24 pivoted at its center as shown

at 25 to the door and terminally engaged with reversely disposed hooks 26 on the ends of the side walls as shown in Figure 1.

Handles 27 consisting of metal tubes are adapted for arrangement in operative relation with the vault, being held by means of the lower straps 28 and the upper strap 29 which transversely span the vault with the extremities of the lower straps hinged as at 30 to form swinging arms 31. These 60 hinges are provided with bolts which may be removed to detach the handles from the vault before lowering the same into the grave.

The structure disclosed while having the 65 durability of hard wood and even metal boards is of much less weight than them and is adapted to resist the action of moisture for an indefinite length of time.

Having described the invention, what is 70 claimed as new and useful is:—

1. A burial vault having a skeleton frame provided with inner and outer linings of wall board to the latter of which is attached metal lathing covered by a plastic protective 75 coating.

2. A burial vault having a skeleton frame provided with inner and outer linings of wall board to the latter of which is attached metal lathing covered by a plastic protective 80 coating, the frame consisting of longitudinal base and spring bars connected by transverse arched frame members.

3. A burial vault having a skeleton frame provided with inner and outer linings of 85 wall board to the latter of which is attached metal lathing covered by a plastic protective coating, the frame consisting of longitudinal base and spring bars connected by transverse arched frame members, and one end of the structure being permanently closed and the other provided with a removable door having a transversely spanning latch bar.

4. A burial vault having a skeleton frame provided with inner and outer linings of 95 wall board to the latter of which is attached metal lathing covered by a plastic protective coating, in combination with handle bars and transverse upper and lower straps span- 100

ning the vault and terminally connected with said bars.

5. A burial vault having a skeleton frame provided with inner and outer linings of wall board to the latter of which is attached metal lathing covered by a plastic protective coating, in combination with handle bars and transverse upper and lower straps spanning the vault and terminally connected

with said bars, the terminals of the lower straps being pivotally mounted to form detachable arms whereby the handles may be removed from the vault.

In testimony whereof they affix their signatures.

BENJIMAN MORTON BIRD.
GEORGE C. BIRD.
DAVID P. BIRD.
